(57) **CLAIM**

The ornamental design for a golf ball dimple head and club grip spatula, as shown and described.

DESCRIPTION

FIG. 1 is a top isometric view of a golf ball dimple head and club grip spatula showing the dimple designed golf ball shaped food handling area and the club like grip arrangement of my new spatula design;

FIG. 2 is a top view thereof;

FIG. 3 is a right side view thereof, the left side view being a mirror image thereof;

FIG. 4 is a bottom view thereof;

FIG. 5 is a front view thereof; and,

FIG. 6 is a back view thereof.
